Patented Sept. 22, 1914.

FIG I

FIG II

UNITED STATES PATENT OFFICE.

ALEXANDER GRANGER, OF BULAWAYO, RHODESIA, SOUTH AFRICA.

PULVERIZING APPARATUS.

1,111,454.

Specification of Letters Patent.

Patented Sept. 22, 1914.

Application filed October 28, 1913. Serial No. 797,749.

To all whom it may concern:

Be it known that I, ALEXANDER GRANGER, subject of the King of Great Britain, residing at Bulawayo, Rhodesia, South Africa, 5 have invented a new and useful Improvement in Pulverizing Apparatus; and I do hereby declare the following to be a full, clear, and exact description of the same.

The present invention has reference to 10 apparatus for pulverizing ore, clinker and other hard material, the purpose being to provide apparatus in which both crushing and grinding may be effected efficiently and with economy of power, which is also compact and requires no expensive supports.

Apparatus according to this invention is shown in the accompanying drawings in which Figure I is a vertical section on the line A—A Fig. II; and Fig. II is a front 20 view partly in section.

1 is a mortar box having a substantial base to serve as a mortar and fitted with a removable cover 2. At the front of the mortar box is a discharge opening 3 which 25 may be fitted with a screen 4 or not as required; at the back of the mortar box is the feed slot 5 through which is passed the material to be pulverized. The mortar box carries a rotatable shaft 6 which operates one 30 or more pulverizing elements 7, two being shown. The said pulverizing elements may vary in form, but are conveniently circular and may therefore be referred to as disks. Each disk is formed with a slot 8 through 35 which a polygonal portion 9 of the shaft 6 passes with a sliding fit, so that the disk 7 rotates positively with the shaft but is free to slide thereon in the direction of its slot 8. Consequently as the disk is rotated 40 it tends to drop at each half revolution when its slot 8 becomes substantially vertical. The two disks shown are positioned on the shaft with their slots 8 at right angles with one another so that one disk rotates a 45 quarter revolution in advance of the other and drops alternately therewith. When there are more than two disks they are suitably arranged to operate in sequence.

Secured to the shaft 6 at the outside of 50 each disk 7 is a collar 10 of elongated form which covers in the adjacent slot 8, and between the disks is another collar 11 also secured to the shaft and covering the slots 8 of both the disks. Said collars 10, 11 are 55 formed with recesses 12 which retain wear-

ing strips 13 on the wearing faces of the shaft 6.

The disks are fitted with renewable tires 14 which may be retained in place by means of wedges 15 on their inner surfaces. The 60 central permanent portion 16 of each disk is provided with peripheral bayonet slots 17, 18 and as the tire is passed laterally onto portion 16, said wedges are passed through the lateral arms 17 of the bayonet slots. 65 Upon the tire being then rotated backwardly upon the portion 16, the wedges 15 wedge up into the circumferentially wedge-shaped arms 18 of the bayonet slots. Thus the tire is firmly but removably 70 secured; and when worn may be dismounted and replaced in a different position upon the portion 16 to bring fresh wearing surfaces into operative position. The bayonet slots may be filled with fusible metal when 75 the tire is in place.

The wearing surfaces of the slots 8 are fitted with renewable liners 19, which may be held in grooves 20 extending from the periphery of the portions 16 of the disks, so 80 that the tires 14 retain said liners 19 in place.

For each disk there is provided a renewable die 21. The upper surface 22 of the die is shaped to form a concave crushing surface 85 extending substantially from the feed aperture 5 to the discharge aperture 4, and being preferably of greater radius than the disk 7. The dies 21 are sunk in curved recesses 23 and are retained therein by the 90 fixed lug 24 and the movable wedging bar 25. The latter upon being drawn up by bolts 26 presses down the rear end of the die and so brings the die to a firm bearing on the mortar and against lug 24. The 95 front and rear ends of the dies are made symmetrical as shown so that the dies may be turned end for end when worn.

The length of the drop of the disks is regulated by raising or lowering the shaft 100 6. For this purpose in the example illustrated each shaft bearing 27 is formed with a saddle extension 28 which is slid over the side of the mortar box and retains packing blocks 29 which sustain the bearing. The bearing is held down by bolts 30 taking into the mortar box, and the blocks 29 are formed with interlocking steps 31 which prevent their lateral movement while the bearing is held down. Upon unbolting and raising the 105 110

bearing, one or more packing blocks 29 may be disengaged and slipped out of the open front 32 of the saddle, and another or others substituted if necessary.

- 5 In operation ore is fed into the feed slot 5, water being also added in the case of wet crushing. Upon the shaft being rotated a disk which is in the position of that shown in the front of Fig. I and at the right hand 10 of Fig. II is rotated eccentrically with the shaft 6 and after making a half revolution,—when its slot again becomes substantially vertical,—it drops upon and crushes the ore lying on the die. After each drop the continued rotation causes the disk to travel over the forward part of the face of the die 21, and so grind the ore lying thereon. While being so ground the material is also swept 15 up toward the discharge opening 3 and is thus eliminated from the mortar box as rapidly as possible. Owing to their respective slots 8 being at right angles, the two disks drop and grind alternately with one another.
- 20 As the dies 21 and tires 14 wear away, the height of the drop is maintained, if necessary, by progressively lowering the shaft 6. However, in practice such adjustment for wear is not usually necessary, since the 25 increased drop due to wear, compensates for the diminished dropping weight. Consequently the apparatus may be run for long periods without adjustment and with no loss of efficiency; the increased drop not being a 30 source of danger as it is in a cam actuated stamp.

It will be understood that in order to cause the disks to drop, the center of the shaft 6 is positioned at a higher point than 40 the center of the disk 7 when the latter is lying on the die, as in Fig. I; the greater the distance between said points, the greater the drop, which is in fact twice said distance. Conversely by lowering the shaft 6 45 the length of the drop and the amount of crushing done are reduced, while the grinding effect remains substantially unchanged; and in the limiting case when the distance between the die and the center of the shaft 50 6 is equal to the radius of the disk 7, crushing is eliminated and the operation is one of grinding only.

The tires wear principally at the parts 55 adjacent to the ends of the slot 8, and when so worn they may be taken off, turned a quarter revolution and replaced for further use. Similarly the dies wear principally at their front ends and may be turned end for end when worn.

60 By reason of its grinding action the apparatus is well adapted to amalgamate precious metal ores while reducing them.

What I claim and desire to secure by Letters Patent is:—

- 65 1. In a pulverizer, a mortar, a pulverizing

body formed with a diametral slot, and a rotatable shaft passing through said body and having a non-circular portion which engages in the slot to rotate positively the body while leaving it free to slide transversely on the shaft, said body being positioned to coöperate with the mortar. 70

2. In a pulverizer, a mortar providing a crushing surface, a pulverizing body formed with a diametral slot, and a rotatable shaft 75 passing through said body and having a non-circular portion which engages in the slot to rotate positively the body while leaving it free to slide transversely, said shaft being elevated above the crushing surface by 80 a distance greater than the radius of the grinding body, whereby the body is caused to drop as the shaft rotates.

3. In a pulverizer, a mortar, a plurality of pulverizing bodies each formed with a 85 diametral slot, and a rotatable shaft passing through said bodies and having a non-circular portion which engages in said slots to rotate positively the bodies while leaving them free to slide transversely thereon, the 90 slots of the different bodies being disposed in different radial directions from one another.

4. In a pulverizer, a mortar, a pulverizing body formed with a diametral slot, a rotatable shaft passing through said body and having a non-circular portion which engages in the slot to rotate positively the body while leaving it free to slide transversely on the shaft, and collars fixed to the 100 shaft and covering said slot.

5. In a pulverizer, a pulverizing body formed with a diametral slot, a rotatable shaft passing through said body and having a non-circular portion which engages in the 105 slot to rotate positively the body while leaving it free to slide transversely on the shaft whereby the body tends to be raised and to fall during each semi-revolution of the shaft, and a mortar having a crushing surface disposed for the body to move over 110 while rotating after the drop.

6. In a pulverizer, a pulverizing body formed with a diametral slot, a rotatable shaft passing through said body and having a non-circular portion which engages in the slot to rotate positively the body while leaving it free to slide transversely on the shaft whereby the body tends to be raised and to fall during each semi-revolution of 120 the shaft, and a mortar having an arcuate crushing surface disposed for the body to move over while rotating after the drop.

7. In a pulverizer, a mortar having a rear feed aperture a front discharge aperture 125 and a concave crushing surface extending between said apertures, a pulverizing body coöperating with said surface and formed with a diametral slot, a rotatable shaft passing through said body and having a non- 130

circular portion which engages the slot to rotate positively the body while leaving it free to slide transversely of the shaft.

8. In a pulverizer, a mortar having a rear feed aperture a front discharge aperture and a concave crushing surface extending between said apertures, a pulverizing body cooperating with said surface and formed with a diametral slot, a rotatable shaft passing through said body and having a non-circular portion which engages the slot to rotate positively the body while leaving it free to slide transversely of the shaft,

whereby the body tends to be raised and to fall during the revolution of the shaft 15 and means for adjusting the shaft at various heights with respect to the mortar and to thereby vary the drop of the body.

In testimony whereof, I have signed my name to this specification in the presence of 20 two subscribing witnesses.

ALEXANDER GRANGER.
